UNITED STATES PATENT OFFICE.

WILLIAM M. SIMMONS, OF BURLINGTON, IOWA.

MEANS FOR OPERATING DOORS OF VEHICLES.

1,076,165.

Specification of Letters Patent.

Patented Oct. 21, 1913.

Application filed August 30, 1912. Serial No. 717,983.

To all whom it may concern:

Be it known that I, WILLIAM M. SIMMONS, a citizen of the United States, residing at Burlington, in the county of Des Moines 5 and State of Iowa, have invented certain new and useful Improvements in Means for Operating Doors of Vehicles; and I do hereby declare the following to be a full, clear, and exact description of the invention, such 10 as will enable others skilled in the art to which it appertains to make and use the same.

My invention relates to improvements in means for operating doors of vehicles and 15 more particularly to opening and closing means for the doors of automobiles,—one object of the invention being to so construct vehicle door operating mechanism that the door cannot be opened or closed without 20 operating the emergency brake of the machine.

A further object is to construct and arrange vehicle door operating mechanism, in such manner, that the application of the 25 emergency brake will render the door operating mechanism operable for opening the door when the latter has been unlatched.

A further object is to so construct the devices that the release of the emergency 30 brake will operate to render the door operating mechanism inoperable to open the door.

A further object is to provide door operating mechanism for vehicles which will 35 serve to prevent the opening of the door when the vehicle is in motion, and to insure the closing of the door when the brake is released on the starting of the vehicle.

With these and other objects in view, the 40 invention consists in certain novel features of construction and combinations of parts as hereinafter set forth and pointed out in the claims.

In the accompanying drawings, Figure 1 45 is a view showing the application of my improvements; Fig. 2 is a view showing the positions of the parts when the doors are open, and Fig. 3 is a view showing the positions of the parts when the doors are open. 50 1 represents portions of an automobile body provided with a hinged door 2 in one or both sides. The door 2 is provided with a latch 3 to engage in a tubular keeper 4 mounted in the body 1, said latch being of any well known or approved construction. 55 A plunger 5 is also mounted in the tubular

keeper 4 and is provided with stem 6, with which latter, one end of a pitman 7 is connected, the other end of said pitman being connected with the crank 8 of an operating lever 9. A spring 10 encircling the stem 5 tends to retain the plunger 5 at the rear end of its throw (with the latch 3 engaging the keeper) and the lever 9 in its normal position. By moving the lever 9 from its normal position, the plunger 5 will be moved 65 rearwardly and, engaging the latch 3, will move the latter out of locked relation to the keeper,—thus unlocking the door.

While door locking devices will be employed in conjunction with the opening and closing mechanism hereinafter described, the specific construction of locking or latch devices hereinbefore described does not constitute a part of the invention herein claimed, 70 but is made the subject of a separate application filed even date herewith.

When the automobile is provided with diametrically opposite doors, each of said doors has secured thereto adjacent to its 75 hinged edge, a bracket 11 to which one end of a rod or pitman 12 is pivotally connected. The other end of each rod or pitman 12 is pivotally attached to a coupling block 13. A horizontal shaft 14 is suitably mounted 80 on the vehicle and provided at its ends with upwardly-projecting arms 15, the upper portion of each of the latter being pivotally connected with one of the coupling blocks 13. It is apparent that if the shaft 14 be 85 imparted in one direction motion will be 90 imparted, through arms 15, coupling blocks 13, rods 12 and brackets 11, to open the doors, and that motion of said shaft in the reverse direction will cause the doors to be closed. 95

The shaft 14 is provided between its ends with an arm 16 which enters a slot 17 in a block 18. This block is also provided with slots 19 in which a pin 20, secured to the arm 16 is movable, and to this pin, one end 100 of a spring 21 is connected, the other end of said spring being secured to a fixed part of the automobile structure. A rod 22 is adjustably secured at one end to the slotted block 18 and at the other end, this rod is 105 adjustably secured to a coupling block 23. The block 23 is pivotally attached to an arm 24 on a shaft 25 and to this shaft, the hand lever 26 of the emergency brake is secured. When the doors are closed and the 110 brake lever is in "release" position, as shown in Fig. 2, the arm 16 on shaft 14

will project forwardly and downwardly from said shaft. The brake lever will be held in this position by the detent and segment devices commonly employed with such levers, and consequently, the shaft 14 will be prevented from turning, and the doors will therefore be retained locked in their closed positions.

In bringing the car to a stop, the operator will apply his emergency brake and in doing so, he will move the block 18 rearwardly on the pin 20, and, as the doors are still latched, the tension of the spring 21 will remain on the arm 16. The car having come to a stop, the operator will manipulate the lever 9 to release the latches of the doors from their keepers, whereupon the spring 21 will be free to turn the shaft 14 and impart motion to the doors, as above described, to open said doors. Motion of the brake lever in a direction to release the brakes, will operate the shaft 14 in the reverse direction and close the doors, permitting their latches automatically to engage their keepers.

From the construction and arrangement of parts herein described, it will be seen the doors cannot be opened while the brake is in released position, and that said doors can be opened only after the brake has been applied.

Various changes might be made in the details of construction of my invention without departing from the spirit thereof or limiting its scope and hence I do not wish to restrict myself to the precise details herein set forth.

Having fully described my invention what I claim as new and desire to secure by Letters-Patent, is:—

1. In door operating mechanism for automobiles, the combination with a door and a brake lever, of devices connecting the door with the brake lever and tending to lock the door when the brake lever is in released position and tending to open the door when the brake lever is moved to set the brake.
2. In door operating mechanism for automobiles, the combination with a door and latch devices therefor, of a rock-shaft, connections between said rock-shaft and the door, an arm on said shaft, an operating lever, a rod connected with said lever and having sliding connection with said arm on the rock shaft for turning the latter in one direction, means for locking said lever to lock the rock shaft, and means for rocking said shaft in the other direction when the operating lever is moved rearwardly.
3. In door operating mechanism for automobiles, the combination with a door and a brake lever, of operating devices connecting

the brake lever with the door for closing the latter, latch devices for the door, means for operating said latch devices to release the door, and a spring connected with said operating devices for opening the door when the brake lever has been moved to set the brakes.

4. In door operating mechanism for automobiles, the combination with a door and a brake lever, of a rock-shaft, an arm projecting from said shaft, lost-motion connections between said arm and the brake lever for turning said shaft in one direction, means for locking said brake lever to lock the shaft in one position, another arm on said shaft, connections between said last-mentioned arm and the door, and a spring for turning said shaft in the reverse direction when the lever is in "set" position.

5. In door operating mechanism for automobiles, the combination with a door and a brake lever, of a rock-shaft, an arm on said shaft, pivotal connections between said arm and the door, a spring connected with said arm for turning said shaft in a direction to open the door, another arm on said shaft, lost-motion connections between said last-mentioned arm and the brake lever, and means for locking the brake lever to lock the shaft when the door is closed and the brake lever is in "release" position.

6. In door operating mechanism for automobile doors, the combination with a door and a brake lever, of a shaft, an arm on said shaft, connections between said arm and the door for imparting motion to the latter, another arm on said shaft, a block having two slots into one of which said last-mentioned arm enters, a pin on said last-mentioned arm and movable in the other slot of said block, a rod attached to said block, connections between said rod and the brake lever, and a spring fixed at one end and connected at its other end with the pin on said last-mentioned arm.

7. In door operating mechanism, the combination with a door, a lever, and means for locking the lever, of connections between said lever and door for closing and locking the door when said lever is moved in one direction, and a spring co-operating to said connections and tending to open the door when said lever is moved in the other direction.

In testimony whereof, I have signed this specification in the presence of two subscribing witnesses.

WILLIAM M. SIMMONS.
